United States Patent Office

Des. 186,967
Patented Dec. 29, 1959

186,967

PORTABLE GRILLE

Milo E. Webster, Rochester, and Francesco Collura, New York, N.Y., assignors to Otto Bernz Company, Inc., Rochester, N.Y., a corporation of New York

Application October 30, 1957, Serial No. 48,283

Term of patent 14 years

(Cl. D81-10)

Fig. 1 is a front perspective view of a portable grille;
 Fig. 2 is a rear perspective view thereof with the grid handle broken away for convenience of illustration;

Fig. 3 is a top plan view thereof on a slightly enlarged scale.

The broken line showing in Fig. 1 is for purposes of illustration only.

We claim:

The ornamental design for a portable grille, as shown and described.
